UNITED STATES PATENT OFFICE.

WILLIAM ALLEN, OF JOHNSTOWN, PENNSYLVANIA, ASSIGNOR TO ALLEN CUT-GLASS COMPANY, A CORPORATION OF PENNSYLVANIA.

DESIGN FOR A CUT-GLASS VESSEL.

Specification for Design.

Patented July 15, 1913.

•44,330.

Application filed March 11, 1913. Serial No. 753,641. Term of patent 3½ years.

To all whom it may concern:

Be it known that I, WILLIAM ALLEN, a citizen of the United States, residing in the city of Johnstown, in the county of Cambria and State of Pennsylvania, have invented a new, original, and ornamental Design for Cut-Glass Vessels, of which the following is a specification, reference being had to the accompanying drawing, forming part thereof.

The figure is a side elevation of a cut-glass vessel showing my new design.

I claim:

The ornamental design for a cut-glass vessel, as shown.

WILLIAM ALLEN.

Witnesses:

J. EARL OGLE,
R. P. SMITH.
